UNITED STATES PATENT OFFICE.

ROBERT J. BAKER, OF BALTIMORE, MARYLAND, ASSIGNOR OF ONE-THIRD
TO JOSEPH MAISCH, OF SAME PLACE.

AUTOMATIC FIRE-ALARM.

SPECIFICATION forming part of Letters Patent No. 600,765, dated March 15, 1898.

Application filed April 28, 1897. Serial No. 634,225. (No model.)

To all whom it may concern.

Be it known that I, ROBERT J. BAKER, residing at Baltimore, in the State of Maryland, have invented a new and useful Automatic 5 Fire-Alarm, of which the following is a specification.

My invention relates to an automatic fire-alarm for use in warehouses, factories, hotels, dwellings, &c., and it may be used in conjunction with the local fire-alarm system or not, as desired.

The object of my invention is to provide an automatic alarm which will indicate in what portion of the building fire has been started and at the same time sound an alarm and, if used in conjunction with the local fire system, will through suitable mechanism sound an alarm at the fire-station and by the alarm indicate in what district the alarm was turned in. I accomplish this object by providing a suitable alarm placed in a box of any dimension and locating in the circuit of the alarm an indicator. Throughout the several rooms of a house I locate wires leading from the indicator and normally have the wire in open circuit. I also place thermostats in position in the wire circuit, so that when there is any great amount of heat in the room they will act to close the circuit and sound the alarm. I also provide automatic means in connection with the box whereby the hinged front will drop to expose the indicator, and also, if the alarm is used in connection with the local fire system, the falling front will permit suitable mechanism to operate to sound an alarm at the fire-station.

My invention, broadly stated, consists of the above arrangement of parts and of certain details of novel construction of the several parts, all of which will be hereinafter more fully described, and specifically pointed out in the claims.

In order that my invention may be fully understood, I will proceed to describe the same, 45 with reference to the accompanying drawings, in which—

Figure 1 is a front elevation of the automatic alarm with the hinged front down to disclose the indicator and the several parts 50 of the alarm. Fig. 2 is a transverse sectional view of the box with the hinged front in closed

position. Fig. 3 is a detail view of the thermostat used in the wire circuit throughout the several views. Fig. 4 is a plan view of the same with the top removed. Fig. 5 is a fragmentary detail view on an enlarged scale, 55 showing one of the contact-arms of the thermostat, illustrating also in dotted lines the position it assumes when heated. Fig. 6 is a detail sectional view of the mechanism on 60 the dotted lines 6 6 of Fig. 2 used for sounding an alarm in the engine-station. Fig. 7 is a diagrammatic view of the alarm and the manner of wiring a building.

In the said drawings, A represents the box 65 or casing of my automatic alarm, which may be of any desired size or configuration as may be found convenient. It is preferably provided with the hinged front B, having the word "Fire" placed on the inside of the front 70 in luminous paint, and this front is for the purpose hereinafter stated. The casing is also provided with the hinged door C in one of the other sides, so that the mechanism contained in the box can be easily reached or 75 inspected.

In the box or casing A, I preferably locate the several parts of my automatic alarm, which is composed of the indicator, the alarm-bell and mechanism for operating it, and the 80 automatic catch for allowing the front to fall. As will be seen from Fig. 1, the hinged front is in such a position in the box that it will fall by gravity when the catch is operated and be assisted in its fall by the weight of the 85 magnets.

The indicator D used in the alarm may be of any desired construction and be of any size. One wire from each station is passed through a common opening in the indicator-casing, and each wire has two branches D' leading therefrom, which are run to that part of the building which the indicator will designate. The other wires from each station in the indicator are bunched and connected 90 with a common wire K', which leads to the magnets of the catch.

The alarm is composed of the usual bell E, magnets E', and the clapper E², which is carried by the armature F. The arrangement 95 of clapper and armature which I use in this connection is as follows: The armature F is

hinged at one end to the box or casing, as shown at F', while its other end F² is bent downward and opens and closes a switch, so that the alarm will be continuously sounded.

5 The switch consists of the two springs G and G', secured at one of their ends in any desired manner and having their contacting ends in the path of the end F². It will be understood (see Fig. 7) that one pole Z from 10 the battery is connected with one pole of the magnets E', and the wire leading from the magnets E' is connected with one of the springs, while the other spring G' is connected by a wire G² with the magnets of the catch.

15 Thus it will be seen that when the armature is attracted to the magnets the end F² will descend upon the spring G to break the circuit, so that the spring G⁴ will pull the clapper E² against the bell. Of course as the end F² is 20 moved away the circuit will be completed and the armature drawn down again. By this means a continuous ringing is kept up.

The automatic catch carried by the hinged front B, and which is operated to allow the 25 front to drop, consists of the magnets H, which are in the circuit of the wire G², and the armature H', which engages the hook H² on top of the box. The armature H' has the springs H³, carried by the pins I, normally bearing 30 against it to keep it in engagement with the hook. The pins I are carried by the guard I', which holds the magnets in place on the hinged front.

35 I³ represents a slotted plate which allows for the adjustment of the magnets toward or away from the armature.

It will be understood that the several parts above described are suitably located in the box so that when a fire is indicated they will 40 operate.

The manner of connecting the several parts so that they will operate is as follows: One pole of the battery is connected with one pole of the bell-magnets E' by the wire Z, while 45 the other wire Z' of the battery is carried to the several rooms of the building, as seen in Fig. 7. After leaving the magnets E' the circuit passes through the springs G and G' into the magnets H of the catch through the wire 50 G², and after leaving the magnets H it passes through the wire K', which is connected with the wires of one pole of the magnets of the indicator of the several stations. The other wire from each station-indicator, as above 55 stated, is passed through an opening in the casing, which bunches them, and each of these wires is provided with two branches, which lead to that part of the building designated by the indicator. These two wires and battery-wire Z' run to each portion of the building, and at those points I locate my improved 60 form of thermostat, which is shown in Figs. 3, 4, and 5. This thermostat consists of a back plate L, of porcelain or other non-conducting 65 material, edge blocks having grooves in their upper surfaces, in which are located the wires from the battery and indicator, the contacting

mechanism, and a perforated cover of porcelain or other non-conducting material. The contacting mechanism consists of an iron bow 70 L⁵, in contact with the battery-wire, having arms L² reaching to a position adjacent to the indicator-wires. A set-screw regulates the normal position of these arms. On the inner side of each arm is rigidly secured a bar L³, 75 of copper or some metal which, while being a conductor of electricity, is expansible to a greater extent than iron under the application of heat. These bars L³ are provided at their outer ends with angular toes or contact-points M. When, under ordinary temperature, the normal position of the contact-points M is out of contact with the indicator-points, the application of a degree of heat in excess of a safe temperature will cause the outer 80 ends of arms L² and the bars L³ to become curved outward owing to the greater expansion of bars L³, which, as clearly shown in dotted lines in Fig. 6, will cause the toes or points M to contact with the indicator-wires, 85 thus closing the circuit through the indicator and sounding an alarm.

It will be seen from the foregoing that I have provided an insulating means in connection with a thermostat and that owing to 95 the arrangement there will be no uninsulated wire exposed, thereby avoiding accidental fires often caused by the uninsulated portion of the wire coming into contact with an electric wire, which causes a spark. The advantage of having two wires is that if one should get out of order the other will be ready to complete the circuit.

So far I have only described that part of my invention which is designed for use in a building and not in conjunction with the local fire system, and it will be seen from the foregoing description that I have provided an exceedingly simple and effective arrangement for indicating fire in any part of a building. It 105 will also be observed that I have described the several parts arranged in what is known as an "open circuit," and it will be understood that an equally effective result could be obtained in a closed circuit.

If it is desired to use my automatic alarm in connection with the local fire system, I provide the usual clockwork system N on the casing, to which the wires from a battery located in the fire-station are connected. In 110 the clockwork I provide the wheel N', having the pins N², which are so arranged as to sound the bell in the engine-house, and which is in this circuit, to indicate the number of the individual box, so that the call can be located 115 at once. The wires leading from the battery in the engine-house terminate in the spring-arms N³ N⁴, one of which, N³, is always in contact with the wheel N', while arm N⁴ is in the path of the pins N², so that when the pins engage the arm the alarm will be sounded. In 120 order to have this mechanism operate in connection with the fire-box, I connect the hinged front B with the drum O of the clock mech-

anism by the chain O', so that when the front falls the chain will unwind and allow the side to drop gradually. In order to hold the clock mechanism when the hinged front is in position, I provide the spring P, which engages one of the train of wheels of the clock mechanism, so that it cannot unwind to sound the fire-alarm.

Q represents a switch for throwing out the arm N³ to prevent an alarm being sounded at the engine-house when it is desired to inspect the box or try the wires in the building.

It will be understood that the alarm proper can be used independently of the local system or in connection therewith, or, if preferred, a separate and distinct circuit can be employed to give an alarm in the fire-station.

Having thus described my invention, what I claim as new, and desire to secure by Letters Patent, is—

1. The combination with the door and the casing provided with the catch, of an angular bracket having slotted arms in contact with the door, screws through the slots for adjustably securing the bracket to the door, magnet-coils mounted on the upright arms of the bracket, a bracket, I, secured to the door, provided with openings through which the coils pass and smaller side openings, the armature, pins projecting back therefrom through the side openings of bracket I, and springs around the pins, bearing against the armature and the bracket I to hold the armature normally in engagement with the catch, substantially as described.
2. In an automatic fire-alarm, the combination of a box or casing adapted to be secured to a wall, an alarm-bell mounted on a standard secured to the back of the box or casing, a pair of magnets mounted on a bracket secured to the back of the casing below the bell, the armature, F, of said magnets, having the

downwardly-bent end, F², hinged in lugs, F', secured to the back of the casing and carrying a bell-clapper, a spring connecting the armature with the standards of the alarm-bell, two contact-plates, G and G', in the alarm-circuit, secured to the side of the casing, the former under the latter and in the path of movement of the end F² of the armature, substantially as described.

3. A thermostat, comprising an insulated iron bow in contact with the battery-wire and having outwardly-projected arms extending toward the indicator-wires, parallel with the battery-wires, bars of different expansibility lying against and rigidly secured to the inside of said arms and provided with angular toes or contact-points adjacent to the indicator-wires, and a set-screw for adjusting the spread of the bow, substantially as described.

4. A thermostat, comprising an iron bow in contact with the battery-wire but otherwise insulated and having its arms extending toward the indicator-wires, a set-screw through the bow for regulating the amount of spread of the arms, and copper bars rigidly secured to the inside of the arms and provided with angular toes or contact-points, substantially as described.

5. The thermostat herein described, consisting of the non-conducting back plate, the edge blocks provided with grooves to receive indicator-wires, the iron bow having spreading arms, secured to the back plate in contact with the battery-wire, the copper bars rigidly secured to the inside of the iron arms and having contact toes or points, and the set-screw for regulating the spread of the bow, substantially as described.

ROBERT J. BAKER.
